UNITED STATES PATENT OFFICE.

HENRY WALDSCHMIDT, OF BENSON, ILLINOIS.

LANTERN-HOLDER.

No. 826,294.

Specification of Letters Patent.

Patented July 17, 1906.

Application filed December 6, 1905. Serial No. 290,600.

To all whom it may concern:

Be it known that I, HENRY WALDSCHMIDT, a citizen of the United States, and a resident of Benson, in the county of Woodford and State of Illinois, have invented a new and Improved Lantern-Holder, of which the following is a full, clear, and exact description.

This invention relates to improvements in holders for lanterns or lamps used on vehicles—such as buggies, wagons, and the like—the object being to provide a holder that will be simple in construction, inexpensive, and having no parts liable to get out of order, and that may be readily placed in position.

I will describe a lantern-holder embodying my invention and then point out the novel features in the appended claims.

Reference is to be had to the accompanying drawings, forming a part of this specification, in which similar characters of reference indicate corresponding parts in all the figures.

Figure 1 is a perspective view of a lantern-holder embodying my invention. Fig. 2 is a sectional elevation thereof. Fig. 3 is a section on the line 3 3 of Fig. 2, and Fig. 4 shows a supporting-pin that may be employed in some instances.

Referring to the drawings, 5 designates a base-plate of suitable material—such, for instance, as metal—and this plate is secured to a device for attaching the holder to the front bow of a buggy-top or the like. This holder consists of a plate 6, adapted to rest upon the top of the bow and having downwardly-extended front members 7, from which clamping-jaws 8 extend inward. These clamping-jaws 8 have tapped holes for receiving set-screws 9. On the set-screws are washers 10, in which the set-screws may freely turn, and these washers are provided with points or lugs 11, designed to engage in the bow and prevent rotary movement of the washers.

The holding device proper consists of two semicircular members 12, which are designed to swing apart relatively to each other and to swing over the plate. The ends of the members 12 are made in the form of a hinged jaw and are perforated to engage upon the pivot-pin 13, rigidly attached to the plate 5 and having a screw-thread engaged by a thumb-nut 14. At the front of the plate 5 are upwardly-extended lugs 15, pivotally connected, to which is a locking-yoke 16. This locking-yoke has two spaced side members which are mounted to swing on pivots 17 passed through the lugs, as clearly indicated in Fig.

3, and the locking device is provided with a handle 18. The free ends of the members 12 are turned outward, as indicated at 19, to pass between the side members of the locking device, and the said side members of the locking device are provided with perforations to receive a split pin 20, which when in position preferably engages in a notch 21, formed in the outwardly-extended portions 19.

In the operation when the lantern or lamp is placed upon the plate 5 the members 12 are moved inward to engage upon the flange of the lantern or lamp. Then the locking device 16 is to be turned upward over the projections 19 and the pin 20 inserted, as clearly shown in the drawings. In some instances it may be desired to place a lamp, such as are used on the sides of carriages, at the center or at the sides of the vehicle. In such case I employ pins 22, (see Fig. 4,) which on the removal of the plate 5 and the locking device may be placed in a hole 23 in the center of the plate 6 or in holes 23^a at the ends of said plate, the lamp being suspended on said pin.

Having thus described my invention, I claim as new and desire to secure by Letters Patent—

1. A support for a lantern or lamp for a vehicle, comprising a plate, a threaded pin rigidly attached to said plate, semicircular members mounted to swing on said pin, a thumb-nut for engaging with the thread of the pin, the free ends of said semicircular members being turned outward, lugs at the front of the plate, and a locking device mounted to swing on said lugs and adapted to engage over said outwardly-turned portions.

2. A lantern or lamp-holder comprising a plate, means for securing the same to a vehicle-top, a threaded pin extended upward from the rear side of the plate, semicircular holding members mounted to swing on said pin, a thumb-nut engaging with the pin, the free ends of said semicircular members being turned outward and notched at the top, lugs on the forward portion of the plate, a locking device having swinging connection with the lugs, the said locking device having perforations and a split pin for passing through said perforations and engaging in said notches.

3. A lantern or lamp-holder for a vehicle, comprising a plate, semicircular holding members having swinging connection with the plate, means for locking said members in closed position, a plate to which the first-

named plate is attached, the said last-named plate being adapted to engage upon the upper portion of a top bow or the like, the said plate having inwardly-turned members for engaging the under side of said bow, and fastening-screws passing through said inwardly-turned portions.

In testimony whereof I have signed my name to this specification in the presence of two subscribing witnesses.

HENRY WALDSCHMIDT.
